UNITED STATES PATENT OFFICE

OMER W. VANDERVELDEN, OF FOREST GROVE, OREGON

STEREOTYPE CASTER

Application filed March 29, 1928. Serial No. 265,737.

This invention relates to stereotype casting machines of the kind especially adapted for use by small newspaper publishers and jobbing print shops for casting stereotype plates for matrices furnished by various agencies. It is of course understood that while this invention is applicable to machines of this type, it is also applicable for casting of other stereotyping plates.

10 A primary object of the invention is to provide a caster of this character, the parts of which are so constructed and mounted to avoid all possibility of spilling the molten metal during the pouring process.

15 Another object of the invention is to so construct the plates or platens between which the matrix is placed that they will be gravity held in place for the pouring of the molten metal and the back plate, when separated, will retain its standing position.

20 Still another object is to mount the molten metal receptacle forward of the center of gravity in order that it will always retain position when not actually used.

25 Another object is to so construct and mount the funnel in relation to the pouring spout as to avoid any possibility of spilling of the molten metal during the pouring operation and to avoid burning of the mat from contact with the molten metal; also to insure a perfect casting by the elimination of dross and foreign matter.

30 In carrying out these objects, the invention is susceptible of modification without departing from the spirit of sacrificing any of the advantages of the claimed invention; there being shown in the drawings for illustrative purposes a preferred and practical form, in which:

35 Figure 1 represents a perspective view of a caster constructed in accordance with this invention with the two plates shown in horizontal position;

40 Fig. 2 is a longitudinal vertical section with the platens shown in upswung vertical positions ready to receive the molten metal, a portion of which has been poured into the casting chamber between the platens, and the metal containing receptacle shown in position to effect such pouring; and

45 Fig. 3 is a perspective view with the lower platen shown swung down into horizontal position and the upper platen back so that the matrix and gauge bars may be properly positioned on the inner face of the lower platen or the poured casting removed.

50 In the embodiment illustrated, the supporting frame includes a rectangular framework comprising longitudinally extending side members 1 connected by transversely extending members 2 which are bolted together and mounted on legs 3 at the front thereof and legs 4 at the rear, the latter being extended above the framework to form supporting means for the metal receptacle presently to be described. The members constituting the framework are preferably formed of angle iron and are suitably braced as shown at 6. The transverse connecting members 2^a which are located at the rear of the frame are preferably positioned on top of the side bars 1 and between the standards 5 formed as extensions of the rear legs 4.

55 The side bars 1 extend at their rear ends beyond the standards 5 and are designed to support a tank 7 for holding gasoline or other liquid fuel which is fed through a pipe 8 to a burner not shown which is positioned beneath the melting pot or receptacle 20. This burner may be of any suitable or desired construction. It is of course understood that this burner should be so constructed and mounted that a pot of cold metal subjected to heat therefrom may be brought to the desired fluid state in a very short period of time.

60 Swingably mounted on the side members 1 of the framework and hingedly connected with each other at one end is what we will term a bottom platen 10 and a top platen 11. The bottom platen 10 is provided on its pivoted or lower end with longitudinally extending hinge knuckles 12 arranged in the same plane as the body portion of the platen and through which extends pintles 13 which not only connect the platens but pivotally connect them with upstanding brackets 15 mounted on the side bars 1 at points spaced slightly in advance of the standards 5.

65 The upper platen 11 is provided on its

100

lower end with inwardly and laterally extending hinge knuckles 14 which project at right angles to the platen 11 and which are positioned adjacent the inner faces of the 5 knuckles 12 of the platen 10 and are designed to receive the pintles 13 whereby the two platens are hingedly connected with each other and pivotally connected with the framework. This providing of the right angularly 10 extending hinge knuckles 14 on the lower end of the platen 11 adapts said platen to be held and remain in upright position as shown in Fig. 3 without requiring any auxiliary fastening means. This is due to the fact that 15 these laterally extending knuckles 14 pivotally connect said platens with the pintles 13 in offset relation, so that when the platen is swung upward it will be off center and thus be held by gravity in this position. Moreover, this arrangement of the hinge knuckles 20 and the connection with the two platens provides for the holding of the platens in upright position when they are connected together to receive the molten metal as shown 25 in Fig. 2 and it also provides for one plate or both standing upright without the use of any locks or latches.

In Fig. 3 the platens are shown in open position with the cast stereotype shown on 30 the bottom platen. This position is also what may be termed the "make-up" position, which is the position occupied by the platens when preparing them for the reception 35 of the molten metal before the castings are stereotyped. The platens are held in spaced relationship and the molten metal is confined in the casting chamber formed between the platens by gauges of any desired construction. In the embodiment illustrated, the gauges comprise longitudinally 40 extending bars 31 and 32 and a transversely extending bar 33. These bars are held together by the clamping action of the two platens and the bars 31 and 32 may be moved 45 toward or away from each other so that castings of various widths may be made.

The matrix (not shown) is placed against the upper face of the lower platen 10 and the gauge bars 31, 32 and 33 are placed thereover in the desired positions. The bars 31 50 and 32 are provided at their outer ends with handles 34 which project beyond the platens when in operative position and may be used to facilitate the manipulation of the connected platens, as well as for the manipulation 55 of the bars in relation to each other.

When the matrix and the gauges are properly positioned the upper platen 11 may be 60 swung down against the upper faces of the gauge bars without causing any movement of the lower platen and without causing the bars to shift on the platen. It is understood that when the platens 10 and 11 with the matrix are arranged as described and locked 65 together by the locking elements 19, a cast-

ing chamber will be provided between the bars 31, 32 and the opposed faces of the matrix on platen 10 and over which is arranged platen 11, the transverse bar 33 forming a bottom for said chamber. The opening to receive the molten metal is formed at the upper end of the connected platens, as is clearly seen in Fig. 2.

The locking elements 19 are preferably constructed in the form of quick acting 75 clamps of the construction shown in the drawings and each comprises a threaded rod or bolt 35 pivoted at one end in the notch 18 of the platen 10 and adapted to swing downward and upward to permit the platen 11 to be positioned over or released from the platen 10. This rod 35, when the platen 11 is swung down over platen 10, enters one of the notches 18^a at the sides of the platen 11 and thereby holds the platens against sliding movement 80 relative to each other and when the sleeve 36 which is threadedly mounted on the rod 35 is screwed down into clamping engagement with the outer face of the platen 11, the two platens are securely locked together 85 and held against swinging toward or away from each other. Operating handles 37 for the sleeves 36 are shown passed transversely therethrough for turning the sleeves into clamping or releasing position, providing the 90 necessary leverage to securely clamp the platens in operative positions.

After the platens have been locked together with the matrix between them in the manner above described, they may then be 100 swung from the horizontal position shown in Fig. 1 to the vertical position shown in Fig. 2, or vice versa. The metal pot or receptacle 20 is pivotally mounted on the standards 5, the pivot or trunnion 21 being shown located 105 forward of the center of the receptacle so that said receptacle will always retain its position when not in use, and yet permit it to be freely swung downward to bring the spout 22 thereof into register with the funnel 110 23 which is positioned to register with the open upper end of the casting chamber between the platens when the platens are in upswung position, as shown clearly in Fig. 2.

The funnel 23 is shown mounted on a cross 115 plate or bar 40 which is mounted between the standards 5 and has laterally extending ends 41 bolted to said standards, as is shown clearly in Figs. 2 and 3. This funnel 23 is open throughout its length at the inner side thereof, as shown at 24 to adapt it to receive the spout 22 when the receptacle 20 is tilted on its trunnions to pour the metal, the walls of said funnel operating as guides for the spout.

An operating handle or lever 25 is prefer- 125 ably secured to one end of the vessel 20 to facilitate the tilting thereof for placing it into operative and inoperative position. The depth of the funnel from its open face to its rear wall is such as to take care of any 130

variation in the position of the pouring spout 22 in its travel during the different tilting stages of the pot 20 during the pouring operation. The outer or rear wall of the funnel 5 is curved at its lower end as shown in Fig. 2 and operates to deflect the molten metal from the spout 22 away from the mat and direct it against the platen 11 thereby avoiding burning of the mat by contact with the hot metal.

10 It will thus be seen that the entering hot metal follows the rear side of the casting chamber to the bottom where it spreads and rises equally at all points causing any dross or foreign matter to float upward and thus 15 produce perfect castings. This feature works equally well when the pot is quite full and the pouring spout 22 is high in the funnel as it does when the pot is nearly empty and the spout is low.

20 Plates 26 and 27 are preferably arranged at the ends of the receptacle 20 being bolted or otherwise secured to the standards 5 and which are designed for retaining the heat beneath the receptacle and thereby facilitate 25 the rapid melting of the metal which is to be used in pouring the casting. It will thus be seen that the funnel 23 may be arranged in close relation to the metal vessel 20 so that when the vessel is begun to be tilted the spout 30 22 thereof will pass immediately into the funnel through the slot 24 therein and thus avoid all possibility of any spilling of the molten metal.

It will thus be seen that a strong simple 25 apparatus is provided and one in which the platens will be gravity held in position for the pouring of the metal avoiding the necessity of using any auxiliary fastening means for this purpose, and which provides also for 40 the retention of the back or upper plate in upright position when separated from the lower plate.

Without further description it is thought 45 that the features and advantages of the invention will be readily apparent to those skilled in the art, and it will of course be understood that changes in the form, proportion and minor details of construction may be resorted to, without departing from 50 the spirit and scope of the claimed invention.

I claim:

1. A stereotype casting machine comprising a supporting frame, a pair of platens 55 pivotally mounted on said frame and hinged to each other to swing vertically in regard to the frame, one of said platens having hinge knuckles extending in longitudinal alignment with the body of the platen and 60 the other platen having hinge knuckles extending at right angles to its body and toward the first mentioned platen whereby when said platens are separated the second mentioned will remain in raised position and 65 when closed they will fit flat against each

other and either one or both platens will stand upright without fastenings.

2. A stereotype casting machine comprising a frame, a pair of platens pivotally mounted on said frame to swing vertically in relation thereto, a molten metal pouring receptacle pivotally mounted on said frame in a plane above said platens, a funnel arranged adjacent said receptacle and adapted to be positioned over the space between the platens when the latter are in raised position, said funnel having a longitudinally extending slot to receive the spout of the pouring receptacle when the latter is tilted, said funnel having means for deflecting the poured material from the spout to prevent the burning of the matrix thereby. 70 75 80

3. A stereotype casting machine comprising a frame, a pair of platens pivotally mounted on said frame to swing vertically in relation thereto, a molten metal pouring receptacle pivotally mounted on said frame in a plane above said platens, a funnel arranged adjacent said receptacle and adapted to be positioned over the space between the platens when the latter are in raised position, said funnel having a longitudinally extending slot to receive the spout of the pouring receptacle when the latter is tilted, said funnel having its rear wall curved to direct the molten metal from the pouring spout into the space between the platen and to cause it to flow out of contact with the matrix during its passage into said space. 85 90 95 100

Signed at Forest Grove in the county of Washington and State of Oregon, this 19th day of March A. D. 1928.
